UNITED STATES PATENT OFFICE.

ARCHIBALD PICKEN, OF ROANOKE, VIRGINIA.

GARMENT-FASTENER.

SPECIFICATION forming part of Letters Patent No. 529,748, dated November 27, 1894.

Application filed November 20, 1893. Serial No. 491,508. (No model.)

To all whom it may concern:

Be it known that I, ARCHIBALD PICKEN, a citizen of the United States, residing at Roanoke, in the county of Roanoke and State of 5 Virginia, have invented a new and useful Fastening for Garments, &c., of which the following is a specification.

My invention relates to a fastening appliance, something in the nature of a hook and eye, to be used on garments, or upon any other article to which it can be applied for the purpose of fastening. Its object is to provide a simple, strong, and secure device which is easily fastened, and unfastened, and which 10 has the advantage of being brought together and fastened at the exact point to which it is brought, without its being necessary to carry the hook a distance behind the catch and after being caught to come forward again, 15 thereby having a certain amount of slackness in the garment so fastened. I attain these objects by the mechanism illustrated in the accompanying drawings, in which—

Figure 1 shows a perspective view of hook 25 B and catch C, and shows them as the hook is about to enter the catch. Fig. 2 shows a perspective view of the parts after they are fastened. Fig. 3 shows a perspective view of the appliance while being taken apart or unfastened, and Fig. 4 shows a vertical section of the appliance while fastened as in Fig. 2.

Similar letters refer to similar parts throughout the several views.

The hook B is a flat piece of material, having a projecting point, prong, or spur E E on each opposite side, these projecting points E E being inclined upward and rearwardly from the surface of the hook B, and serve to open the parallel bows A A of the catch C, and after 35 passing between them, allow them to close behind, the projecting points E E thereby securing the hook as in Fig. 2.

The catch C corresponds to what is usually the eye of a hook and eye. It is composed of 45 two parallel bows A A made in one piece with and held together by the spring G, and opening when forced apart by the hook B and projecting inclined points E E, and closing behind the projecting points E E thereby 50 securing it as in Fig. 2.

The two sections A A of the bowed portion

of the device are made of one piece of wire bent into a loop or eye G to form a spring at the side to hold the sections A A together, and have their ends on the other side bent 55 into eyes G' G'. The loop or bend of the spring G and the eyes G' G' form attaching points for the thread which secures this part of the device to the garment. The hook B, is withdrawn from the catch C by being turned 60 edgewise, as in Fig. 3, the edges J J of hook B holding the parallel parts A A of the catch C apart, and releasing the points E E of the hook allowing the hook to be withdrawn. The hook B may have either one or two projecting points. If one, it will be on one side; if two, there will be one on each opposite side as in the drawings. The use of but one point instead of two would not materially alter the effect of the hook. The parallel bows A A 65 of catch C may be held together by a spring same as G in the drawings, or by one formed in any other way that will answer the same purpose and preserve the principle of the catch as herein set forth.

In defining my invention with greater clearness, I would state that I am aware that it is not broadly new to provide a scarf pin with an annular recess, and combine it with a holder composed of two convolutions of 70 spring wire, constructed after the manner of a split ring, which clamp the pin and lie in the recess to form a holder or lock for the point. My invention is distinctive in these features; that the edges J J of the hook project beyond the points or spurs E, and the body of the hook B is broad and flat so that when turned edgewise, as in Fig. 3, the bows A A are separated thereby for easy disconnection of the parts; also further in the fact 75 that the spring G serves the three fold purpose of connecting the bows A A, providing a spring pressure for clamping them together, and also a point of anchorage for connecting the catch C to the garment by means of the 80 thread.

Having thus described my invention, what I claim as new, and desire to secure by Letters Patent, is—

1. The fastener herein described, consisting 85 of the hook composed of a flat body portion with one or more inclined and rearwardly

pointing prongs or spurs projecting away from the plane of the body portion, and the catch or holder consisting of two parallel bowed parts held together by spring tension, substantially as and for the purpose described.

2. The combination with a hook consisting of a flat body portion and one or more inclined rearwardly projecting prongs or spurs; of a

catch or holder composed of two parallel bowed portions made in one piece and bent at one side into a spring loop or eye, and having at the other side a terminal eye substantially as and for the purpose described.

ARCHIBALD PICKEN.
